DESIGN FOR A TOY GUN

Don G. McAfee, Grand Rapids, Mich.

Application February 12, 1945, Serial No. 117,894

Term of patent 7 years

(Cl. D34—15)

To all whom it may concern:

Be it known that I, Don G. McAfee, a citizen of the United States, residing at Grand Rapids, in the county of Kent and State of Michigan, have invented a new, original, and ornamental Design for a Toy Gun, of which the following is a specification, reference being had to the accompanying drawing, forming part thereof.

Fig. 1 is a side perspective view of a toy gun showing my new design, and

Fig. 2 is a perspective view showing the opposite side thereof.

I claim:

The ornamental design for a toy gun, substantially as shown.

DON G. McAFFEE.
